UNITED STATES PATENT OFFICE.

ISRAEL MAGIDSON, JOSEPH ARENZ, AND OTTO PFEFFERKORN, OF MILWAUKEE,
WISCONSIN.

CIGAR-PACKING DEVICE.

1,410,109.

Specification of Letters Patent. Patented Mar. 21, 1922.

Application filed September 12, 1919. Serial No. 323,300.

To all whom it may concern:

Be it known that we, ISRAEL MAGIDSON, JOSEPH ARENZ, and OTTO PFEFFERKORN, all citizens of the United States, and residents 5 of the city of Milwaukee, county of Milwaukee, and State of Wisconsin, have invented certain new and useful Improvements in Cigar-Packaging Devices; and we do declare the following to be a full, clear, and 10 exact description thereof, such as will enable persons skilled in the art to which the invention pertains to make and use the same, reference being had to the drawings hereto attached for disclosure as to details of construction and arrangement.

Our invention relates to a device or apparatus for packing cigars in cylindrical containers.

Such invention comprises means for 20 pressing a bundle containing the required number of cigars, so that such bundle of cigars may be inserted as a unit in the container; also means for discharging the unit from the compressor into the container with 25 facility and without damage to the wrappers of the cigars.

The increasing cost of wooden boxes for cigars has brought into public favor with the trade, the use of cylindrical jars and 30 cans of glass and tin, respectively, and many cigars of high grade and of well known brands, neatly packed in glass jars, are now being offered to consumers.

Heretofore, it has been the practice to 35 pack the cigars in the glass and tin containers by hand, but with the growing demand for cigars packed in this manner, there has been a very large increase in the cost of labor. In the better grades of 40 cigars, when packed in glass jars, it has been the practice to arrange the outer row of cigars with their label bands so that the latter will be visible from any point of view, thus adding to the artistic effect of the 45 package.

The purpose of our invention is the production of a device which will enable the cigars to be packed swiftly and economically, and at the same time preserve all the 50 pleasing effects of the old methods of packing by hand. We have achieved this very desirable result by a construction in which the cigars are loosely assembled in a compressor, and while loosely held, the label 55 bands of the outer row of cigars are faced

outwardly, so that such labels will appear in uniform order when the bundle or unit of cigars is inserted in the glass jar. After such arrangement is completed, the bundle of cigars is compressed to the diameter necessary to correspond with the opening in the jar, and by means of a plunger the bundle or unit is pushed out of the compressor and into the container.

In the form in which our invention has 60 been embodied, the compressor is made from a strip of spring sheet brass possessing the requisite degree of resiliency, rolled into the form of a short tube with overlapping edges, 70 and is provided with a handle on each edge, whereby the operator may readily adjust the compressor to the different positions in which it works, and at the same time hold the cigars from any accidental displacement or disarrangement from the time of their 75 assembly until finally placed in the container.

In carrying out our invention, the cigars are first assembled in the compressor, which is then placed between the jaws of a squeezing press, which latter is operated to reduce the bundle of cigars to the desired diameter. This having been done, the compressor with 80 its unit of cigars is placed over the container, and the plunger brought in use to 85 discharge the unit and fill the container.

The specific description of our invention, as hereafter given, recites the employment of the invention in connection with glass containers, but it will be understood that 90 the invention may be used with equal facility in packing cigars in tin cans, and also for packing the cheaper grades of cigars in round pasteboard or heavy paper boxes.

In the claims at the close of this specification, we shall point out the novel features 95 of our invention.

In the drawings forming a part of this specification,

Figure 1 is a plan view of that element 100 of our invention which we call the compressor, the latter being shown as provided with a funnel by means of which the cigars are passed into the compressor in the act of assembly, and also as resting on the rotatable 105 stand or block, the functions of which will be described hereinafter.

Figure 2 is a vertical sectional view on the line 2-2, Figure 1, showing the relative arrangement of the parts above referred to. 110

Figure 3 is a plan view of the squeezing press, in which the compressor with its charge of cigars is placed, and which imparts the desired diameter to the bundle or unit of cigars.

Figure 4 is a vertical section on the line 4—4, Figure 3, showing the interior of the squeezing press.

Figure 5 is a view in elevation showing 10 the arrangement of the several elements preparatory to the act of discharging a bundle or unit of cigars from the compressor into a container; and

Figure 6 is a vertical sectional view on the 15 line 6—6, Figure 5, showing the manner of the engagement of the compressor with the interior of the container, whereby the former is positioned for accurate discharge of the bundle or unit of cigars, as described.

Like reference characters identify the 20 same parts in all of the views.

In the drawings, A indicates a rectangular or other outline of base upon which certain of the elements of our invention are 25 mounted.

At one side of the base, a circular stand or block B, is journaled upon a screw b, which passes through a central opening in the said stand or block, and into the base A, where- 30 by the said stand or block may rotate about the screw, if desired. The said stand or block B, is turned so as to provide a step or shoulder b¹, and a circumferential recess b², between the step or shoulder and the face 35 of the stand or block. The walls of the recess are inclined, as shown at b³.

The compressor C, is formed from a strip or sheet of spring brass c, rolled into a short tube. A lining c¹, of like but thinner ma- 40 terial, is placed inside of the spring member c. The length of the lining c¹ exceeds that of the part c, so that the ends of the lining section overlap to complete the circle. One end of the part c is brought into register 45 with one end of the lining c¹, and at this point a handle D is secured by rivets which unite the three elements. At a point adjacent the other end of the part c, a second handle D¹, is secured in a like manner by rivets 50 passing as before. It will be observed that the free end of the lining c¹, is bevelled as at c², and that the edge bears closely against the outer coil, so as to pass without obstruction around the cigars being assembled. 55 The resiliency of the compressor acts to hold the latter open, but with one hand the operator may reduce the opening by grasping the handles D and D¹, and drawing them together.

In assembling the cigars, the lower edge of the compressor is set in the circumferential groove b², in the stand or block B, and a funnel E, may be placed in the open top of the compressor, to facilitate the insertion of 65 the cigars, the blunt ends of which rest upon

the face of the said stand or block. The engagement of the lower edge of the compressor C in the groove b², prevents expansion of the former while the cigars are being assembled. After the required number of 70 cigars have been placed in position, those forming the outer row are faced so that the brand labels on the cigar will be exposed at all sides of the bundle, the funnel having been previously removed, so that the labels 75 are exposed above the top of the compressor. The rotatable mounting enables the operator to face the work in arranging the outer row of cigars.

At another place on the base A, a squeezing press F, shown in plan in Figure 3, is arranged. This press is composed of a fixed part or jaw f, and a hinged part or jaw f¹, the former being attached, by screws passing through a flange, to the base A, and provided with a hinge portion f². Both jaws are recessed to form a circular opening, as shown. The part f¹ is formed with a complementary hinge portion f³, and the two parts or jaws of the press are joined by a pin f⁴, which passes through both of the hinge portions. Each of the hollowed out parts of the press may be provided upon its interior with ribs f⁵, extending horizontally and circumferentially. 95

The hinged or pivoted part f¹, of the press is provided with a socket piece f⁶, in which a handle f⁷, is inserted, and with an arm f⁸, having a longitudinal slot f⁹, in which is placed an adjustable stop f¹⁰, the latter contacting with the edge of the base A, to limit the inward movement of the hinged part f¹, and thus determine the diameter to which the bundle of cigars is to be reduced for convenient insertion in the container. 105

The compressor, having been filled with cigars assembled as previously described, is grasped by the operator taking hold of the two handles, and with its load or bundle, is transferred from the stand or block B, to the 110 squeezing press F, being placed between the recesses of the hollowed out jaws or parts of the latter. A momentary relaxation of the initial pressure upon the cigars in the bundle will permit them to slide down inside of 115 the compressor, until their blunt ends rest upon the base A. The jaws of the press are now caused to approach each other by swinging the lever f⁷, until further movement is resisted by the stop f¹⁰. At this time, the 120 bundle of cigars will have been so compressed or reduced in diameter, that it will fit easily into the receptacle or container.

The compressor C is provided with lugs or projections c⁴, at points upon its circumference, and arranged in the plane in which the lower edge of the handles lie. The lugs or projections c⁴, and the portion of the handles, as described, serve to act as stops to 125 limit the downward movement of the com- 130

pressor when the latter with its charge of cigars, is placed in the open mouth of the container.

The container G, is shown in Figure 5, as 5 constituted of a clear glass jar. Upon the completion of the compression of the bundle of cigars in the squeezing press, the operator, without relaxing the pressure upon the bundle, grasps the handles D and D¹, and transfers the compressor to the container and inserts the lower end of the compressor therein, the latter being supported on the jar as described. Upon releasing the pressure upon the handles, the compressor will expand until 15 the latter fills the open mouth of the jar. A plunger H, comprising a head h, and a handle h¹, is employed for discharging the bundle of cigars from the compressor into the container, by application in the manner shown in Figure 5. In practice, the whole 20 charge of cigars is moved without disarranging their order or damaging them in any way.

By our invention, we have produced an 25 economical cigar packing device, which has enabled us to greatly increase the output in a given length of time, and at a very great saving of expense over the methods of packing cigars heretofore employed.

30 It will be understood that modifications may be made without departing from the spirit of our invention. The dimensions of the various elements will be varied to accord with the diameter of the bundle which it is desired to produce.

Having thus described our invention, what we claim and desire to secure by Letters Patent, is:

1. In a cigar packing device, a compressor, 40 a stand for retaining the compressor while cigars are being placed therein, a squeezing press, and means for applying pressure to the cigars while the compressor is moved from the stand to the press.

45 2. In a cigar packing device, a compressor, a stand for retaining the compressor while cigars are being placed therein, a squeezing press, and means on the compressor, to apply pressure to the cigars while the compressor is moved from the stand to the press.

50 3. In a cigar packing device, a resilient compressor provided with means for applying initial compression to the cigars therein, a stand for holding the compressor while be-

ing filled, and a squeezing press acting upon the compressor to reduce the bundle of cigars to the desired diameter.

4. In a cigar packing device, a resilient compressor, a stand for retaining the compressor while cigars are being placed therein, means for applying initial pressure to the cigars, a squeezing press for reducing the bundle of cigars to the desired diameter, and means for discharging the cigars as a unit from the compressor into a container. 65

5. In a cigar packing device, a resilient compressor, means for holding the compressor against expansive movement while being filled with cigars, a squeezing press, means for applying initial pressure to the cigars 70 while the compressor is moved to the press, and means for discharging the cigars as a unit into a container.

6. In a cigar packing device, a compressor in which the cigars are assembled, a squeezing 75 press acting upon the compressor to reduce the bundle of cigars to the desired diameter, and means for discharging the bundle as a unit into a container.

7. In a cigar packing device, a squeezing 80 press, a compressor fitting therein and in which the cigars are assembled, means for operating the press to reduce the bundle of cigars to the desired diameter, and means for discharging the bundle of cigars as a 85 unit into a container.

8. In a cigar packing device, a compressor for holding a bundle of cigars, means for reducing such bundle to the desired diameter, means for limiting the movement of the compressor into a container, and means for discharging the cigars as a unit into a container. 90

9. In a cigar packing device, a tubular compressor for holding a bundle of cigars in 95 cylindrical form, and means for supporting the compressor with the cigars upon a container, in combination with means for discharging the cigars as a unit from the compressor into a container. 100

In testimony whereof, we have signed our names at Milwaukee, this 6th day of September, 1919.

ISRAEL MAGIDSON.
